CLAIM

We claim the ornamental design for a skydiving helmet, as shown and described.

DESCRIPTION

FIG. 1 is a perspective view of a skydiving helmet; FIG. 2 is an enlarged view of a lateral plate shown in FIG. 1;

FIG. 3 is a front elevation view of the skydiving helmet shown in FIG. 1;

FIG. 4 is a rear elevation view of the skydiving helmet shown in FIG. 1;

FIG. 5 is left-side elevation view of the skydiving helmet shown in FIG. 1;

FIG. 6 is right-side elevation view of the skydiving helmet shown in FIG. 1;

FIG. 7 is a top plan view of the skydiving helmet shown in FIG. 1; and,

(Continued)

FIG. 8 is a bottom plan view of the skydiving helmet shown in FIG. 1.

The broken lines illustrate portions of the skydiving helmet and form no part of the claimed design.

1 Claim, 7 Drawing Sheets
